UNITED STATES PATENT OFFICE.

ALEXANDER MCKENZIE, OF KIPPE, ONTARIO, CANADA.

BELLY-BAND ATTACHMENT.

1,123,566.

Specification of Letters Patent.

Patented Jan. 5, 1915.

Application filed January 31, 1914. Serial No. 815,767.

To all whom it may concern:

Be it known that I, ALEXANDER MCKENZIE, a subject of the King of Great Britain, residing at Kippen, in the Province of Ontario and Dominion of Canada, have invented certain new and useful Improvements in Belly-Band Attachments, of which the following is a specification.

This invention relates to an improved plate which is secured to the belly-band of a harness and provided with eyes with which snap hooks carried by the martingale and breeching straps are connected. By means of this plate the belly-band is prevented from being worn through, and also the ends of the martingale and breeching straps are prevented from being worn through by frictional wear between the belly-band, martingale, and breeching straps. This construction will also cause a saving of leather since the martingale and breeching straps do not have to be provided with large loops through which the belly-band may pass.

This invention is illustrated in the accompanying drawings wherein:

Figure 1 is a plan view showing the martingale and breeching straps connected with the plate; Fig. 2 is a view showing the plate secured to the belly-band; Fig. 3 is an elevation showing the plate secured to the belly-band.

The plate 10 which is curved longitudinally as shown in Figs. 2 and 3 is secured to the belly-band 11 by means of rivets 12 and is provided at a point adjacent its center with a forward eye 13 and rear eye 14.

The martingale 15 carries a snap hook 16 which engages the eye 13 and the breeching straps 17 carry snap hooks 18 which engage the eye 14. After the harness has been put on and the belly-band tightened, the hook 16 of the martingale is snapped into the eye 13 and the hooks 18 of the breech-

ing straps 17 are snapped into the eye 14. The breeching straps and martingale will be permitted to have free movement, but there will be no danger of the breeching straps, martingale or belly-band being worn through due to friction. It should also be noted that with this arrangement a great deal of leather may be saved since it is only necessary to double a small portion of the free ends of the martingale and breeching straps in order to connect these with the snap hooks 16 and 18.

This harness may be quickly put in place and quickly removed due to the fact that the hooks can be quickly snapped into and out of place. This plate may be formed from stamped sheet metal or if desired, may be cast according to the size and strength of plate desired. I have thus provided a plate which is so constructed that it may be connected with a belly-band in order to permit the martingale and breeching straps to be releasably connected with the belly-band by means of snap hooks.

What is claimed is:

In a harness a belly band, a plate fitting against the outer face of the belly band, said plate being curved longitudinally to conform to the curvature assumed by the belly band when in use and having means for providing rigid attachment to the belly band, eyes extending from opposite longitudinal side portions of said plate at a point intermediate its length, a martingale, breeching straps, and means carried by said martingale and breeching straps for releasably connecting the same with said eyes.

In testimony whereof I affix my signature in presence of two witnesses.

ALEXANDER MCKENZIE.
